UNITED STATES PATENT OFFICE.

DENIS F. CASHMAN, OF DAYTON, OHIO.

DUAL CONTROL FOR FLYING-MACHINES.

1,177,382.

Specification of Letters Patent. Patented Mar. 28, 1916.

Application filed December 14, 1915. Serial No. 66,810.

To all whom it may concern:

Be it known that I, DENIS F. CASHMAN, a subject of the King of Great Britain, residing at Dayton, in the county of Montgomery and State of Ohio, have invented certain new and useful Improvements in Dual Controls for Flying-Machines; and I do hereby declare the following to be a full, clear, and exact description of the invention, such as will enable others skilled in the art to which it appertains to make and use the same.

The invention relates to improvements in controlling mechanism for flying machines.

The object of the present invention is to improve the construction of controlling mechanism for flying machines and to provide simple, practical and comparatively inexpensive controlling mechanism of light, strong, and durable construction designed for use on various types of flying machines both those heavier than air and of the dirigible type and capable of enabling the machine to be controlled by one or more persons so that in event to injury of one of the pilots the machine may be properly handled by another without changing seats and endangering the machine through loss of control of the same.

A further object of the invention is to provide a controlling mechanism of this character adapted to be controlled by easy and natural movement and capable of operating the elevator plane to lift the machine by a backward movement of the operator and depress the machine by a forward movement and at the same time enable the machine to be guided to the right or left without affecting the position of the elevator plane and by the use of a single controlling element.

It is also the object of the invention to enable the controlling means to be connected with the plane by direct connection so that there will be no liability of slack or necessitate winding and unwinding flexible connections from drums and the like.

With these and other objects in view the invention consists in the construction and novel combination and arrangement of parts hereinafter fully described, illustrated in the accompanying drawings and pointed out in the claims hereto appended, it being understood that various changes in the form, proportion and minor details of construction may be resorted to without departing from

the spirit or sacrificing any of the advantages of the invention.

In the drawings Figure 1 is a plan view of a flying machine provided with a control 60 constructed in accordance with this invention, Fig. 2 is a side elevation of the same, Fig. 3 is an enlarged plan view partly in section illustrating the construction of the controlling mechanism, Fig. 4 is a longitudinal 65 sectional view on the line 4—4 of Fig. 3, Fig. 5 is a transverse sectional view on the line 5—5 of Fig. 3, Fig. 6 is a detail sectional view on the line 6—6 of Fig. 4, Fig. 7 is a detail sectional view of a locking device. 70

Like numerals of reference designate corresponding parts in the several figures of the drawings.

In the accompanying drawings in which is illustrated the preferred embodiment of 75 the invention, the controlling mechanism is shown applied to a monoplane of the Bleriot type but it may be used on various types of flying machines whether aeroplanes or dirigible machines and the said controlling 80 mechanism comprises in its construction one or more longitudinal shafts 1, two of such shafts being illustrated in the accompanying drawings to provide a dual control but the number of the shafts may be varied to 85 provide a control for as many persons or pilots as desired. By providing a means for enabling a plurality of persons to simultaneously and in unison control a flying machine the control of the latter will not 90 be lost and the machine endangered should an accident incapacitate any one of the pilots and the necessity of changing seats in order to obtain control of the machine is thus avoided. The shafts 1 which are 95 equipped at their rear ends with steering or controlling wheels 2 are provided with terminal round portions 3 and 4 which are slidably journaled in suitable bearings 5 and 6 of the frame 7 of the machine or other supporting means. These shafts 1 which may be mounted in any desired manner are provided with a polygonal portion 8 and a round rack portion 9. The polygonal portion which is preferably square is 100 slidable through a corresponding polygonal opening 10 of a transversely disposed pinion 11 held against longitudinal movement by any suitable means and meshing with a transversely movable rack bar 12. The 114 rack bar which is arranged in suitable guides 13 is movable transversely of the

105

100

114

machine and is connected with the front terminals of flexible connections 14 guided by suitable pulleys 15 and connected at their rear ends with the arm 16 of the rudder 17. 5 The rudder 17 is pivoted at its front edge in the usual manner and the arm 16 extends laterally from opposite sides of the rudder. The flexible connections constitute direct connections between the rack bar 12 and the 10 arms of the rudder and when the steering or controlling wheel is turned to the right, the transversely movable rack bar 11 will be carried to the left and will cause the rudder to swing to the right for steering 15 the machine in that direction. By this arrangement the steering or controlling wheel is turned in the direction in which it is desired to steer the machine. The guides 13 which may be of any desired construction 20 are preferably provided with arms 18 located in advance and in rear of the pinion 11 for holding the same against longitudinal movement with the shaft 1. The round rack portions 9 of the shafts 1 mesh with vertically arranged longitudinally disposed 25 pinions 19 which are carried by a transverse shaft 20 journaled in suitable bearings of the frame of the machine and provided with oppositely disposed arms 22^a extending upwardly and downwardly from the transverse shaft 20 and connected by a flexible connection 22 with the elevator plane or planes 23 which are pivoted at their front edges on a horizontal axis in the usual manner and are provided with upwardly and 30 downwardly extending arms 24 and the flexible connections which are attached to the arms 24 cause the elevator plane to tilt upwardly to elevate the machine when the controlling shafts are moved rearwardly 35 and the elevator planes are swung in the opposite directions to depress the machine when the shafts 1 are moved forwardly. The front flexible connections 22 are attached to arms 22^a of the transverse shaft 20. By this construction the elevator planes are operated by natural movement of the pilot or pilots. The longitudinal movement of the shafts 1 may be effected when the 40 rudder is in any position without affecting the latter and the position of the rudder may be changed without affecting the position of the elevator planes. Instead of connecting the controlling mechanism with the 45 rudder and elevator planes as shown in the accompanying drawings it will be apparent that the transversely movable rack bar and the transverse shaft may be connected with the steering and elevating means of 50 various types of flying machines.

While the round rack bars are shown provided with teeth extending entirely around them the length of the arcuate teeth may be varied where it is unnecessary to provide 55 for a complete revolution of the controlling

or operating shaft. Also by having the teeth of the rack portions 9 curved or circular a proper meshing of the rack portions with the pinions 19 will be had at all times and the pinions 19 are preferably provided with curved teeth to conform to the configuration of the round rack bars but the teeth of the pinions 19 may be of any desired configuration which will afford a proper engagement or mesh of the 75 parts.

Any suitable locking means may be employed for securing the longitudinal operating or controlling shaft against rotary and longitudinal movement and in the accompanying drawings the shafts 1 are shown provided with diametrically disposed perforations 25 which are engaged by locking pins 26 operating in diametrically opposite openings 27 of the front bearings 5. 80 85

While the transversely movable rack bar is shown connected with the wire of the rudder it may be used for operating the warping control or the like and the rudder could then be operated by the ordinary foot levers or 90 95 100 105 110 115 120 125 130 135 140 145 150 155 160 165 170 175 180 185 190 195 200 205 210 215 220 225 230 235 240 245 250 255 260 265 270 275 280 285 290 295 300 305 4. Controlling mechanism for flying machines including a plurality of longitudinally disposed controlling shafts mounted for rotary and longitudinal movement and provided with rack portions, a transverse shaft having pinions meshing with the rack portions, a transversely movable rack bar and pinions meshing with the rack bar and slidably interlocked with the longitudinal shaft, and locking means for securing the longitudinal shaft against rotary and longitudinal movement.

5. Controlling mechanism of the class described including a plurality of longitudinal controlling shafts provided at their rear ends with operating devices and having polygonal portions and round rack bars, a transverse shaft having pinions meshing with the rack bars, a transversely movable rack bar and pinions meshing with the transversely movable rack bar and slidably interlocked with the polygonal portions of the longitudinal shaft.

6. Controlling mechanism of the class described including a plurality of longitudinal controlling shafts provided at their rear ends with operating devices and having polygonal portions and round rack bars, a transverse shaft having pinions meshing with the rack bars, a transversely movable rack bar and pinions meshing with the transversely movable rack bar and slidably interlocked with the longitudinal shaft, and locking means for securing the longitudinal shaft against rotary and longitudinal movement.

7. Controlling mechanism for flying machines including a plurality of longitudinally movable controlling shafts provided with rack portions, a transversely disposed shaft having pinions meshing with the rack portions and provided with upwardly and downwardly extending arms, means for connecting the said arms with the elevator plane of a flying machine, a transversely disposed rack bar, pinions slidably interlocked with the controlling shafts and meshing with the transversely disposed rack bar, guiding means located beyond the ends of the transversely disposed rack bar and flexible connections guided by the said guiding means and connected with the ends of the transverse rack bar and designed to extend to the rudder of the flying machine.

In testimony whereof I affix my signature in presence of two witnesses.

DENIS F. CASHMAN.
